GARMENT

Aron Kalb, Astoria, Long Island, N. Y.

Application June 17, 1941, Serial No. 398,376

2 Claims. (Cl. 2—227)

This invention relates to improvements in garments and more particularly to a garment designed for protection against the elements in a manner which affords a maximum of protection while presenting a neat and finished external appearance.

A further object of my invention is to provide a garment of the character described comprising a pair of trousers of relatively heavy material provided with any desired or convenient suspension means having secured interiorly thereof a pair of relatively light, flexible leg covering members, the lower portions of which are provided with reenforced contractile members closed by means of separable fastener elements.

A further object of my invention is to provide a garment comprising a pair of trousers of relatively heavy material to provide a maximum of protection against the elements and having secured interiorly thereof a pair of relatively light leg covering members freely secured thereto to provide a maximum of flexibility and to facilitate the application of the garment, having novel means at the terminal ends of said leg covering members to positively secure the relatively light covering members to the legs of the wearer.

These and other advantageous objects, which will later appear, are accomplished by the simple and practical construction, combination, and arrangements of parts hereinafter described and shown in the accompanying drawing, wherein like reference numerals indicate like parts and wherein:

Fig. 1 is a side elevational view of a garment embodying my invention shown partly in section for the sake of clarity.

Fig. 2 is an enlarged elevational view taken on lines 2—2 of Fig. 1 showing one of the terminal ends of the leg covering members having a cuff member secured thereto with the fastener elements thereof in open position, and

Fig. 3 is a top plan view taken on lines 3—3 of Fig. 1.

In the drawing the garment of my invention is shown to comprise a pair of trousers 10 of relatively heavy material, the lower ends of the trousers being doubled upon themselves and reentrantly bent to provide the trouser ends 11 and an inner protective member comprising a body portion and a pair of leg covering members depending therefrom. The upper edge of the trousers is folded over the upper edge of the body portion of the inner protective member and is sewed or otherwise secured thereto at 12 in a manner to provide a tube like marginal waist

member 13 for the reception of an elastic member 14 to normally tend to contract the marginal member 13 about the waist of the wearer on application of the trousers. The garment is further provided with any desired or convenient suspender and closure elements 15 and 16 respectively. The trousers 10 are preferably made of relatively heavy inflexible material. The inner protective member is secured at its upper 10 marginal edge to the interior of the trousers at 12 as set forth above and the outer sides of the leg covering members are secured to the interior of the adjacent portions 18 of the respective trouser legs to normally hold the leg covering members and their cuff members within and above the lower ends of the trousers and to limit the movement of the leg covering members within the trousers. The trousers 10 are of corresponding features and outline; a description of one 20 will suffice for both; one is shown partly broken away in Fig. 1. The leg covering members 17 are made of light, flexible material so that they will yield freely upon the insertion of the wearer's leg therein, permitting the garment to be applied in a rapid and convenient fashion and obviating the awkwardness inherent in garments of the structure heretofore in common use. As will be noted from Fig. 1 of the drawing, the leg covering members are supported from the waistband of 25 the trousers and the outer side of each leg covering member is secured for substantially the major portion of its length to the interior of the adjacent portion of the respective trouser legs. The terminal ends 19 of the leg covering members are tapered and have marginally secured thereto the closed peripheral edges 21 on contractile cuff members 22. The latter are provided with longitudinal slits 23, whereby said contractile members 22 normally assume an 30 open position as in Fig. 2 so that the garment may be donned in an extremely easy manner, the open ends of the contractile members enabling the thrusting of the leg through the garment with a minimum of effort. After the garment has been donned, the contractile members 22 35 may be closed by means of any suitable separable fastener elements 24 along the slit 23 thereof. The contractile members 22 are preferably made of knitted or other contractile material to provide neat and tight-fitting lower ends for the leg covering members. From the foregoing it will be seen that the garment will present the external appearance of a neat and smooth fitting garment while the wearer's legs are snugly enveloped by the leg covering members which, being

closed by the contractible members 22, provide a maximum of protection from the elements.

Having thus described my invention, what I claim as new and desire to secure by Letters Patent is:

1. A garment comprising a pair of trousers, an inner protective member comprising a pair of leg covering members having open lower ends, said leg covering members being substantially coextensive with the legs of the said pair of trousers and supported from the waistband of the trousers, contractible cuff members secured to the open lower ends of said leg covering members, said cuff members being provided with longitudinal slits to enable them to normally assume an open position to facilitate donning the garment, means carried by the contractible members to close said slits when the garment is worn, the outer side of each leg covering member being secured for substantially the major portion of its length to the interior of the adjacent portion of the respective trouser legs in position to normally hold the leg covering members and their cuff members within and above the open lower ends of the trousers and to limit the movement of the leg covering members within the trousers.

2. A garment comprising a pair of trousers, an

inner protective member comprising a body portion and a pair of leg covering members having open lower ends, the upper edge of the trousers being folded over the upper edge of the body portion of the inner protective member to define a tube-like marginal waist member adapted to receive a member to contract the garment about the wearer's waist, said leg covering members being substantially coextensive with the legs of the said pair of trousers and supported from the waistband of the trousers, contractible cuff members secured to the open lower ends of said leg covering members, said cuff members being provided with longitudinal slits to enable them to normally assume an open position to facilitate donning the garment, means carried by the contractible members to close said slits when the garment is worn, the outer side of each leg covering member being secured for substantially the major portion of its length to the interior of the adjacent portion of the respective trouser legs in position to normally hold the leg covering members and their cuff members within and above the open lower ends of the trousers and to limit the movement of the leg covering members within the trousers.

ARON KALB.
